UNITED STATES PATENT OFFICE.

JOHN T. POWERS, OF DENVER, COLORADO, ASSIGNOR, BY MESNE ASSIGNMENTS, TO THE COMBINATION LOCK COMPANY, OF DENVER, COLORADO, A CORPORATION OF COLORADO.

PERMUTATION LOCK FOR AUTOMOBILES.

Application filed January 14, 1922. Serial No. 529,140.

To all whom it may concern:

Be it known that I, JOHN T. POWERS, a citizen of the United States, residing in the city and county of Denver and State of Colorado, have invented certain new and useful Improvements in Permutation Locks for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to permutation locks and has special reference to a lock adapted to be applied to the gear shift lever of an automobile for the purpose of locking the lever in neutral position.

It has been found from experience that unless an automobile is provided with an effective lock, it is liable to be stolen by persons who make a business of stealing and selling cars, or by young and thoughtless persons who desire to use it for a short time, after which they abandon it in some out-of-the-way place where it is liable to be stolen by a professional thief.

In order to guard against theft, locks of a great many different types have been invented and offered for sale. Experience has proven that a successful lock should be so applied to a car that the latter can be moved, as it often becomes necessary in a city to move a car some short distance, as in the case of a fire nearby or in order that other cars parked to the front or the rear may be moved.

I will not attempt to enumerate the many different types of locks and locking systems that have been tried, as their numbers are very great.

It is the object of this invention to produce a lock that can be applied to the gear shift lever of an automobile, and be so designed that it will lock the same in neutral position. With the gear shift lever locked in neutral position, it is evident that the car cannot be driven by its own power as the engine cannot be coupled to the driving mechanism; at the same time the car can be moved in case of fire or if for any other reason this should be made necessary.

It is the further object of this invention to produce a lock that can be applied to any

of the cars which are provided with a gear shift lever without necessitating any material change in the lever structure or construction, and it is a still further object of this invention to produce a lock that can be used for other purposes as well as for locking the gear shift lever.

In order to more clearly describe my invention, I shall have reference to the accompanying drawing in which—

Fig. 1 is an elevation of an ordinary gear shift lever showing my lock in place thereon, a part of the lock being broken away to more clearly show the lock structure;

Fig. 2 is a front elevation of my lock and shows the arrangement of the locking tumblers and lock plunger;

Fig. 3 is a vertical transverse section of my lock showing it applied to a gear shift lever, a portion of the latter being broken away to show the plunger in locking position;

Fig. 4 is a section on line 4—4, Fig. 2, showing the lock applied to an H-slot gear shifting mechanism;

Fig. 5 is a view of the lock taken on line 5—5, Fig. 3; and

Fig. 6 is a top view of my lock.

The same reference numerals will be used to indicate the same or similar parts throughout the several views.

Numerical 1 indicates a lever which is used for the purpose of shifting the transmission gears, and which I shall refer to hereinafter as the gear shift lever, and 2 is a cast-iron housing to the top of which the lever 1 is connected by means of a ball and socket joint, while the lower part of the housing is bolted to the transmission gear casing (not shown). Housing 2 is usually provided with an upwardly extending flange 3. The gears are so arranged that when lever 1 occupies a vertical position the gears are inoperable, and this position is therefore referred to as the neutral position. It is evident that if a means is provided whereby lever 1 can be positively locked in the neutral position, the car will thereby be secured against operation by means of its own power. In order to be able at will to lock the gear shift lever in its neutral position, I have invented the lock which forms the subject of this application, and which consists of a body member 4 whose lower end 5 is circular in shape and provided with an

axial opening 6 whose lower end is increased in diameter as indicated at 7 and 8. The upper end of body member 4 is flattened and has its flanges 9 inclined so as to make 5 a dove-tail shaped slot 10 which is adapted to receive the member 11 which carries the locking elements. Member 4 is applied to the gear shift lever in the manner clearly shown in Figs. 1 and 3. Located within the 10 enlarged openings 7 and 8 is a spring 12 which is under compression when the lock occupies the locking position and serves to move the lock against the pin 13 when the locking bolt 14 is withdrawn from the socket 15. A second socket 16 is provided for the 15 reception of the plunger 14 when the lock occupies its uppermost or unlocking position. Member 11 is substantially rectangular in shape and has two parallel inclined 20 sides 17 which have sliding engagement with the inclined sides 10 of flanges 9. Substantially centrally of member 11 is an outwardly projecting tubular projection 18, within which is slidably and rotatably 25 mounted a plunger 14, the outer end of which is of less diameter than the inner end and is surrounded by a spring 19 which abuts against the shoulder 20 of the plunger and the flange 21 of tubular member 18, and 30 serves to bias the plunger towards its innermost position.

A knurled head 22 is secured to the outer end of the plunger 14 and serves as a convenient means for moving the same against 35 the tension of the spring 19 and also acts as a stop to limit the inward movement of the plunger. Plunger 14 is provided with an annular groove 23 near its inner end for a purpose to be hereinafter described. 40 Spaced substantially equidistantly from the center of the opening in the tubular member 18 are three holes 24 whose inner ends are counterbored to provide three openings 25, 26 and 27 of different diameters and of 45 varying depth. Located within each opening 25 is a cylindrical tumbler 28 having a cylindrical portion 29 of reduced diameter, which extends through the opening 24 and terminates in a knurled knob 30 by which 50 it may be turned. Tumblers 28 are longitudinally corrugated as indicated by numeral 31. Opening into the side of each opening 25 is a round hole 32 within which is a ball 33 which is biased toward the sides 55 of tumblers 28 by means of a spring 34. Ball 33 serves to produce a faint click as the tumblers rotate and also to prevent them from rotating of their own accord due to vibration. Within the opening 26 is a pin 60 35 which cooperates with pin 36 on tumblers 28 to produce a stop by which the zero position of the tumblers may be determined. Within the opening 27, I place a washer 37, the central hole of which is cut so as to 65 65 form to the shape of the cylinders 28. Each

washer 37 has an arcuate notch 38 of such shape that when the lock is in its unlocked position the three notches cooperate and form an opening of such size that the bolt 14 may freely reciprocate therein. When 70 either one of washers 37 occupy any other position than that described above as the unlocked position, the edge of the washer will project into the annular groove 23 in the plunger 14 in the manner shown in Figs. 75 3 and 5, and prevent the bolt from being withdrawn.

The combination of the lock is set and changed in the following manner: With the member 11 removed from its slot in member 4, the tumblers are all rotated in a clockwise direction until pin 36 strikes stop 35. Tumbler A is then rotated in a counter-clockwise direction for as many notches as desired, for example one. The disc 37 is then 80 put in place with notch 38 embracing plunger 14. Tumbler B is then rotated the desired number of notches, for example two, and the disc 37 applied thereto. Tumbler C is then rotated, for example three notches, 85 and the disc 37 applied thereto in the same manner as with tumblers A and C. It will thus be seen that the combination at which the lock opens is 1, 2, 3, and can be arranged to suit the taste of the owner. When 90 the lock is to be locked, the tumblers are moved any desired number of notches so that the edges of washers 37 may engage in slot 23. To open the lock the tumblers are first turned in a clockwise direction until 100 they are all in zero position; tumbler A is then moved one notch, tumbler B two notches, and tumbler C three notches, if the combination is 1, 2, 3. Either one of the three tumblers can be made to correspond to 105 the first number of the combination, and three separate combinations can then be formed with 1, 2, 3 as the numbers thereof. Instead of rotating the tumblers clockwise to zero and counter-clockwise to the 110 unlocking position, the arrangement may be reversed which would have the same effect as changing the combination. It is therefore evident that my lock possesses an almost endless variety of possible combinations. When the lock has been assembled and set to the desired combination, a thin plate 39 is then put in place on the back side of member 11 and serves to hold the discs 115 37 in place while the lock is put in place 120 in the grooves of member 14. When the lock occupies the position shown in Fig. 3, the plunger 14 cooperates with socket 15 and holds the lock frame 4 from upward movement, thus preventing the gear shift 125 lever 1 from being operated. If the discs 37 are turned so that the edge of one or more of them is in the annular groove 34, it is apparent that plunger 14 cannot be withdrawn from the socket 15 and the lever 1 130

is therefore securely locked. When it is desired to unlock the car, the tumblers A, B and C are rotated to zero position and then set in accordance with the combination; 5 plunger 14 can then be pulled outwardly and entirely removed from socket 15, after which the spring 12 will raise the lock upwardly against stop 13 in which position plunger 14 will engage socket 16 and hold the lock 10 positively in the unlocking position so as to assure that it will not accidentally be shoved downwardly into locking position while the car is being operated. If the car is provided with a gear shift employing the 15 ordinary H-slot shown in Fig. 4, then my lock is applied to the lever 1 in exactly the same manner as it is applied with the type of lever shown in Fig. 1. The lower flange of member 5 is provided with two diametrical 20ly opposed slots 40 which permits the ends 41 to enter therein when the lock is in its lowermost or locking position, by which means it is apparent that the shift lever 1 becomes firmly locked in neutral 25 position.

Although I have described my lock as applied to the gear shift lever of an automobile, it can be employed in many other different relations, and I contemplate employing 30 it for locking the spare tire in place, for locking the garage or other doors, and for almost any purpose for which a lock can be employed. I do not intend to be limited to the specific use pointed out, but desire protection 35 for my lock regardless of the use to which it is put. From the above description, it is evident that I have provided a simple but strong and efficient lock of pleasing appearance, which can be applied to the 40 gear shift lever of an automobile without altering the construction of the latter to any appreciable degree, and which when so applied will effectively lock the gears in neutral position which prevents any unauthorized 45 person from driving the car away under its own power. The car can, of course, be towed away, but it is not practicable to so lock a car that a thief provided with the proper equipment and unmolested in his endeavors, cannot move a car from the position 50 in which it is left by the owner. A car equipped with my lock is reasonably safe from being used by unauthorized persons and from being taken by a professional thief.

Having now described my invention or

discovery, what I claim as new and desire to have protected by Letters Patent, is—

1. A permutation lock adapted to be applied to a gear shift lever, comprising in combination, a body member having an annular flange about its lower end; a pair of opposed inclined flanges forming a passage for the reception of a lock member, a lock member, a bolt reciprocable in said lock member, and rotatable means for locking said bolt against reciprocation.

2. A permutation lock adapted to be applied to a gear shift lever, comprising in combination, a body member having an annular flange about its lower end, a pair of opposed inclined flanges forming a passage for the reception of a lock member, a lock member slidable in said passage, an outwardly projecting tubular member in one side of said locking member, a bolt reciprocable in said tubular member, a spring within said tubular member, a shoulder on said plunger, a cooperating annular flange on the end of said tubular member, a spring surrounding a portion of said plunger and engaging said shoulder and said flange, means for moving said plunger against the tension of said spring, and locking means for holding said plunger against movement in a predetermined position.

3. A permutation lock adapted to be slidably applied to a gear shift lever, comprising a body member having an annular flange at one end, a pair of opposed flanges having inclined sides at the other end, said flanges and sides forming a passageway for the reception of a locking member, a locking member slidably secured to said body member, said locking member being of considerable thickness and substantially rectangular in shape, an outwardly projecting tubular member substantially central on said locking member, a plunger reciprocably mounted in said tubular member, a spring in said tubular member and cooperating with said plunger to hold the latter in a predetermined position, a plurality of tumblers about said plunger, a disc attached to each tumbler and cooperating with a groove in said plunger to lock the same in place, said discs each having a notch, said tumblers having a portion of their sides corrugated, and a spring-pressed detent for operating with said corrugation.

In testimony whereof I affix my signature.

JOHN T. POWERS.
